(57) **CLAIM**

The ornamental design for a shock absorbing hub assembly for supporting a propeller on a marine propulsion apparatus, as shown and described.

DESCRIPTION

FIG. 1 is a front perspective view of a first embodiment of a shock absorbing hub assembly for supporting a propeller on a marine propulsion apparatus.

FIG. 2 is a top view thereof.

FIG. 3 is a bottom view thereof.

FIG. 4 is an end view thereof.

FIG. 5 is an opposite end view thereof.

FIG. 6 is a front perspective view of a second embodiment of a shock absorbing hub assembly for supporting a propeller on a marine propulsion apparatus.

FIG. 7 is a top view thereof.

FIG. 8 is a bottom view thereof.

FIG. 9 is an end view thereof; and,

FIG. 10 is an opposite end view thereof.

The broken lines in the drawings illustrate portions of the shock absorbing hub assembly that form no part of the claimed design.

1 Claim, 8 Drawing Sheets
